UNITED STATES PATENT OFFICE.

GEORGE KNOCK, OF CLEVELAND, OHIO.

FILTER.

1,414,137.

Specification of Letters Patent. Patented Apr. 25, 1922.

Application filed December 26, 1919. Serial No. 347,551.

To all whom it may concern:

Be it known that I, GEORGE KNOCK, a citizen of the United States, residing at Cleveland, in the county of Cuyahoga and State of Ohio, have invented a certain new and useful Improvement in Filters, of which the following is a full, clear, and exact description, reference being had to the accompanying drawings.

This invention relates to filters, and more especially to a filter which is designed to be inserted between a gasoline tank and the carbureter of a motor vehicle. The general purpose and object of the invention is to provide a filter of this character which will effectually prevent the passage of sediment or water therethrough and into the carbureter. A further object of the invention is to provide a filter of this character from which the water and sediment may be conveniently removed, with the filter in either a vertical or a horizontal position. I accomplish these objects in and through the construction and arrangement of parts shown in the drawings forming a part hereof, wherein Fig. 1 represents a side elevation of such filter; Fig. 2 a sectional view corresponding to the line 2—2 of Fig. 1; and Fig. 3 a sectional view corresponding to the line 3—3 of Fig. 2.

Describing the various parts herein by reference characters, 1 denotes a cylindrical casing the opposite ends whereof are shown as seated respectively each within an annular groove formed in the removable heads 2 and 3. With the filter arranged as shown herein, the head 2 is the lower, and the head 3 is the upper, head. The head 2 is provided with a threaded aperture 4, preferably at one side thereof, and with a second threaded aperture 5, preferably at the opposite side thereof. The aperture 4 receives a connection 6 to which the supply pipe 7 may be secured in any desirable manner. This pipe may lead from the vacuum tank to the carbureter in vehicles provided with such vacuum systems; or it may be interposed between a pressure tank and the carbureter, according to the equipment of the particular vehicle to which the filter is applied. Threaded into the aperture 5 is a drain connection 8 having a petcock 9 provided with the usual operating handle 10.

Mounted within the lower end of the casing 1 is a screen 11, of wire gauze, said screen being carried by a ring 12 adapted

to engage the head 2, preferably just outside the apertures 4 and 5. Above the screen 11, there is provided a screen 13, preferably of the same mesh as the screen 11 and carried by a ring 14 projecting upwardly from the peripheral portion thereof. Above the ring 14 is a spacing ring 14^a. In the upper end of the casing 1 there is shown a fine-mesh screen 15, supported at its periphery by a ring 16 which is adapted to engage the head 3. The head 3 is shown as provided with a threaded aperture 17 adapted to receive the connection 18 for the pipe 19 which leads to the carbureter. The space between the screens 11 and 13 will be filled with granulated material 20, preferably charcoal.

In practice, the screen 15 will be of about 140-160-mesh, while the screens 11 and 13 will be of about 60 mesh.

By the use of a filter such as shown and described herein, any water which may enter the chamber 21 beneath the screen 11 will be prevented from passing through the filter by the screen 15, the latter screen, however, permitting the passage of the gasoline. Also the major portion of any sediment which may be in the gasoline will be collected beneath the screen 11. The screens 11 and 13 serve also to support the filter mass 20, while the final screen 15 will positively prevent any water from passing to the pipe 19.

The location of the aperture 5 and the drain outlet 8 enables water and sediment accumulating in the chamber 21 to be removed with the filter in a vertical or a horizontal position, it being necessary only to see that the aperture 5 and its drain connection are at the bottom of the filter when it is employed in the latter position. The filtering material 20 will arrest and retain any sediment that may pass through the screen 11. By opening the petcock, the gasoline supplied through the pipe 7 will serve to flush out any sediment in the chamber between the head 2 and the screen 11.

Having thus described my invention, what I claim is:—

1. A gasoline filter comprising a casing having at one end thereof a supply connection and a drain connection and at the other end an outlet connection, a screen extending across said casing and forming with the end thereof adjacent to the supply connection and the drain connection a collecting chamber, a second screen extending across said

casing and spaced from the first mentioned screen, filtering material in said casing between said screens, and a water-excluding screen of fine mesh wire within the casing 5 and on the opposite side of the second screen from the first screen.

2. A gasoline filter comprising a casing having heads at opposite ends thereof, one of said heads having a supply connection and 10 a drain connection located adjacent to the casing wall, and the other head having an outlet connection, a ring adapted to fit within the casing wall and to bear against the first-mentioned head, a screen supported by 15 said ring and forming with said ring and the adjacent head a chamber communicating with the inlet and drain connections, a second ring within said casing, a screen supported by the second ring, filtering material 20 within said casing and interposed between said screens, a ring interposed between the outlet end of the casing and the second screen, and a water-excluding fine-mesh wire screen supported by the last mentioned ring 25 and interposed between the second head and the second screen.

3. A gasoline filter comprising a casing and heads therefor and provided with a sup-

ply connection and a drain connection at one end thereof, the drain connection being located adjacent to the casing wall, a screen extending across said casing and forming with one of said heads a collecting chamber with which the said connections communicate, a second screen extending across said 35 casing and spaced from the first mentioned screen, filtering material in said casing between said screens, a water-excluding screen of fine-mesh wire within the casing at the opposite side of the filtering material from 40 the first screen, a head beyond the third screen, and an outlet connection beyond such third screen.

4. A gasoline filter comprising a casing having a supply connection and an outlet 45 connection, a pair of relatively coarse screens extending across said casing between the supply and the outlet connection, there being a charcoal filling interposed between said screens, and a water-intercepting screen of 50 fine mesh wire extending across the casing and interposed between the aforesaid filter and the outlet connection.

In testimony whereof, I hereunto affix my signature.

GEORGE KNOCK.
